(57) **CLAIM**

The ornamental design for a stethoscope handle, as shown and described.

DESCRIPTION

FIG. 1 is a top perspective view of a stethoscope handle showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The dashed broken lines in the figures depict portions of the stethoscope handle that form no part of the claimed design.
